UNITED STATES PATENT OFFICE

FREDERICK CARDER, OF CORNING, NEW YORK

DESIGN FOR AN ARTICLE OF BRIC-A-BRAC

Application filed August 28, 1929. Serial No. 32,583. Term of patent 14 years.

To all whom it may concern:

Be it known that I, FREDERICK CARDER, a citizen of the United States, residing at Corning, in the county of Steuben and State of New York, have invented a new, original, and ornamental Design for an Article of Bric-a-brac, of which the following is a specification, reference being had to the accompanying drawings, forming part thereof.

Fig. 1 is a side view in elevation of an article of bric-a-brac, and

Fig. 2 is a top plan view of Fig. 1.

My invention embodies a base 1, the exposed portions of which are suitably finished superimposed upon the base 1 is a transparent body 2 which is provided with a multiplicity of regularly arranged bubbles 3.

I claim:

The ornamental design for an article of bric-a-brac as shown and described.

FREDERICK CARDER.
